5799X J. Leonard, Jr., Brainard & Sizer,

Pattern for Casting.

Patented Jan. 28, 1830.

Jonathan Leonard Junr. and J. Braillard & Amasa Tige

X5799

Letters Patent.

Jan. 28, 1830

The schedule referred to in these Letters Patent and making part of the same containing a description in the words of the said Jonathan Leonard Junr. and J. Braillard & Amasa Tige themselves of their improvement in the construction of Patterns used for forming Moulds for casting Iron, Brass, &c.

Know all men by these presents

That we Jonathan Leonard Junr. of Meriden, J. S. Braillard & Amasa Tige both of Wallingford, have jointly invented a new and useful improvement in the construction of Patterns used in forming Moulds for casting Iron, Brass, or other metal, where a portion of the mould is formed in two or more parts of the flask commonly used for moulding which improvement we specify in the words and figures following

(viz.) In the first place we make in the usual manner one or more patterns, according to the number of articles we intend to cast in a flask, which patterns are made in exact representation of the things we wish eventually to produce, except that they must be large enough to allow for the shrinking of the metal, which takes place both in casting the pattern and the things to be formed in most metals, moulded and cast in the common way. In the next place these patterns are to be imbedded or let into a board or other support, instance one half of them thickness flatwise, & a mould is then to be formed from each pattern, in all respects in the usual manner. If the things to be cast are small, as for instance the common thumb-screws, by a judicious arrangement of them several may be moulded in the same flask, with a view to produce a pattern such as is represented in the annexed drawing, annexed &c. In the next place take some stiff

of wood or other substance about one inch wide, and one and a half
of an inch in thickness, or as thick as the plate represented in each
of each of the drawings is wanted to be 4 of such lengths and
number as that when they are forced together at their ends
they will form a square or such other figure as is needed & as
large as the said plate is intended to be made, the size and
shape of which plate will of course be made to correspond with
the flask to be used in moulding from the plate and pattern attached
to the same, Then place the frame on the sand in the lower part
of a common flask, filled in the usual way and moulded as al-
ready directed so that the frame will keep the metal within
itself & place the upper part of the flask upon the lower part
with the frame between them which will keep the two parts
asunder a small distance equal to its thickness. Some small
pieces of some hard substance should also be placed between
the outer parts of each portion of the flask, which pieces should
be of the thickness of the frame & are of use to prevent the
weight which is to be placed in the usual manner upon the
flask from inembedding the frame into the sand. The sprue hole
should be formed in the usual way at a little distance from
the mould to prevent the metal from washing the mould, &
in that way produce a defect in the pattern. It will be
necessary that a gate way should be formed for each pattern
& not at the same time, or afterwards placed upon the flask
and care must be taken, that the metal should be of a proper
compensation when poured in, that the work may be as
perfect as it can conveniently be made, The plate and
patterns attached to the same being now and should be
cut and finished in the usual way, & if the object is to form
a plate with patterns attached for casting them in
one at a time, the same is illustrated by the annexed drawing
A. B. C. The plate when the finished must be turned over
so as to be the same of thickness as the pattern

now being the object of which is that the plate when used may be kept steady in its place by as many pins of suitable size, passing this the body in the plate and made fast at one end in one part of the flask, and entering when the flask is put together into holes of suitable size and depth made in the other part of the flask. The two parts of the flask with the plate & pattern attached between them and the whole kept steady by the pins being thus prepared are ready to receive the moulding sand, or to be powdered. Each part of the flask, is now to be filled with moulding sand, and then if that part of the flask to which the pins are made fast is uppermost lift off this part of the flask and the plate together, & then take off the plate, but if the other part of the flask is uppermost, take off this part & then take off the plate from the other part, so that in both cases the pins shall quiver the plate during its removal.

By proceeding in the way above specified or with perhaps some slight variation, a pattern or draft plate with raised worked patterns or drafts for most kinds of work which are ordinarily moulded in different parts of a flask, may be prepared, and moulds made therewith as is already described.

The plate might be formed first and the parts of the pottery attached thereto by colouring or otherwise, though with much more difficulty and expense. The plate & the parts of the pottery may be also formed separately in wood and fastened together, & in large & heavy work, this would probably be the better mode.

The whole both plate and pottery, might be carved or cut out of solid wood, but this would also be in general too difficult and expensive.

The advantage attending moulding in the above manner are principally experienced in work of a medium size, with our pottery, less care and skill are required in the process of removing the pottery without disturbing the mould, & if a pattern is attached to a plate by joining or removing a considerable number of patterns at one operation, all the time

111. 135749
in view of protection from working out or beyond the lines
- of or small of the pattern & by that means trifling or con-
- sisting when the pattern is drawn; other less important elements
- they are not mentioned. The Drawing referred to in
the foregoing description is annexed and makes a part of this
specification, together with the annexed description of the
drawing and the reference to the same.

We claim as our specific improvement that we
have invented a new and useful mode of constructing pat-
terns formed of metal, wood, or other suitable material,
& consisting of a plate with raised work or projecting
figures on each side thereof, to be used in making moulds the
parts of which are in different parts of a flask and which
moulds are fitted for casting work in iron or other metal.

But we do not claim the exclusive right of making
Pottery, for moulding, or any mode of using them which
has heretofore been practised.

In testimony that the above is a true specification
of our said joint improvement as above described, we have
hereunto set our hands, and seal, this nineteenth day of
November, A.D. 1829.

Explanation of Drawings A. & B. 1, 2, 3, 4
represent the plate, on which are the raised Patterns, A.
Showing one side, & B. the other side of the plate. D, E, F, the
raised or projecting patterns, G, G, G, a projection to form a
staircase in the mould connected with the space and the
gutter, H, H, H, the gateway for leading sand into the
moulds made by Patterns A, B, C, D, E, F, G, H, I, J, K, L, M, N, O, P,
the middle of which is a top, & the bottom of which is a bottom to put
the sand from the bottom of the moulds into the top of the moulds.
